Primary Examiner — Selina Sikder

(74) *Attorney, Agent, or Firm* — Dinsmore & Shohl LLP

(57) **CLAIM**

We claim the ornamental design for a switch cover, as shown and described.

DESCRIPTION

FIG. 1 is a perspective view of the switch cover showing our new design;

FIG. 2 is a front elevation view thereof;

FIG. 3 a right side elevation view thereof;

FIG. 4 is a left side elevation view thereof;

FIG. 5 is a top plan view thereof;

FIG. 6 is a bottom plan view thereof;

FIG. 7 is a rear elevation view thereof;

FIG. 8 is a perspective thereof shown with a spacer as environment;

FIG. 9 is a front elevation view thereof;

FIG. 10 a right side elevation view thereof;

FIG. 11 is a left side elevation view thereof;

FIG. 12 is a top plan view thereof;

FIG. 13 is a bottom plan view thereof;

FIG. 14 is a rear elevation view thereof;

FIG. 15 is a perspective thereof shown with a spacer as environment;

FIG. 16 is a front elevation view thereof;

FIG. 17 a right side elevation view thereof;

FIG. 18 is a left side elevation view thereof;

FIG. 19 is a top plan view thereof;

FIG. 20 is a bottom plan view thereof; and,

FIG. 21 is a rear elevation view thereof.
